UNITED STATES PATENT OFFICE

2,604,212

COMBINED CLOTHESLINE STRETCHER AND ELEVATOR

Thomas F. Goodwin, Muldrow, Okla.

Application April 14, 1950, Serial No. 155,949

1 Claim. (Cl. 211—119.17)

1 My invention relates to a combined clothesline stretcher and elevator.

A primary object of the invention is to provide a device of the above-mentioned character which will completely eliminate the necessity for the well known forked pole or clothesline prop which is difficult to secure in place, and which requires constant adjustment, the prop also interfering with the hanging of the clothes on the line.

A further object is to provide a combined clothesline stretcher and elevator which is highly simplified in construction, sturdy and durable, inexpensive to manufacture and very easy to manipulate.

A still further object of the invention is to provide a device for raising and lowering a long, substantially horizontal clothesline which is suspended between two upright posts without necessitating the use of any intermediate prop or pole.

Other objects and advantages of the invention will be apparent during the course of the following description.

In the accompanying drawings forming a part of this application, and in which like numerals are employed to designate like parts throughout the same:

Figure 1 is a side elevational view of a combined clothesline stretcher and elevator embodying my invention;

Figure 2 is a similar view of my combined device with the clothesline in the raised or elevated position;

Figure 3 is a plan view of the device illustrated in Figure 1; and

Figure 4 is a perspective view of an elevating bell crank lever removed.

In the drawings, where, for the purpose of illustration, is shown a preferred embodiment of my invention, the numerals 10 and 11 designate upstanding, substantially vertical, fixed posts or poles which may be anchored in the ground and spaced a substantial distance apart. Freely pivotally mounted upon the top ends of the posts 10 and 11 by means of transverse, horizontal pins or bolts 12, or the like, are a pair of vertically swingable, generally L-shaped bell crank levers 13 and 14. These bell crank levers may be arranged close to the adjacent sides of the vertical posts 10 and 11, as shown, and the bell crank levers 13 and 14 include elongated, curved, handle extensions or arms 15, and relatively short, straight extensions or arms 16 integral therewith. Small hooks 17 are freely pivotally connected with the handle extensions 15 near and inwardly of their outer or free ends, and the free

2 ends of the relatively short arms or extensions 16 carry line-attaching eyes 18 integrally secured thereto. An elongated, substantially horizontal clothesline 19 has its opposite ends permanently secured to the eyes 18, as shown. I prefer to make the arms 16 approximately eight inches long, although this length may be varied. It is also desirable that the distance from the ground to the bottom ends of the arms 16, Figure 10 1, be approximately four feet, although this distance may be varied as desired.

In use, the housewife merely disconnects the hooks 17 from the clothesline 19 and swings the bell crank levers 13 and 14 to their positions illustrated in Figure 1. When this has been done, the relatively short arms 16 will be disposed generally vertically and depending from the pivot bolts 12. Accordingly, the horizontal clothesline 19 will be spaced below the top ends of the posts 10 and 12 a distance substantially equal to the length of the arms 16. When the line is in this lowered position, it is very easy for the housewife to hang the clothes upon it. It will be unnecessary to stand on any chair, box or like object, 15 and there is no clothesline prop or separate forked pole to remove and adjust. After the lowered clothesline 19 is filled with clothes, the bell crank levers 13 and 14 are swung in the direction of the arrows in Figure 1 until the arms 30 16 are upwardly directed and extending substantially vertically above the tops of the posts 10 and 11. With the bell crank levers in these positions, the clothesline will be tensioned and the hooks 17 are engaged over the clothesline for releasably locking the handle extensions or arms 15 thereto, 35 Figure 2. The clothesline 19 and the bell crank levers 13 and 14 are now releasably held in substantially their positions illustrated in Figure 2. The clothesline has now been elevated from its original lowered position of Figure 1 to a distance 40 equal to twice the length of one of the arms 16 above the lowered position of the clothesline. If the arms 16 are approximately eight inches long, the clothesline may be raised and lowered approximately sixteen inches by swinging the bell crank levers to and from their positions shown in Figures 1 and 2.

It is thus seen that I have provided a combined device for properly tensioning the clothesline as well as raising and lowering it to a substantial distance while maintaining the line substantially horizontal at all times. The use of my combined device completely eliminates the well known troublesome clothesline prop or forked pole.

55 Although I have shown the bell crank levers

13 and **14** pivotally mounted upon corresponding vertical sides of the upstanding vertical posts **10** and **11**, I do not wish to limit the invention to this precise arrangement. If desired, the bell crank levers **13** and **14** may be pivotally mounted upon the ends of fixed horizontal members or posts, and their operation for raising and lowering and tensioning the clothesline will be exactly the same. Also, if desired, the posts **10** and **11** may be constructed with top horizontal cross members so that the posts are substantially T-shaped. The bell crank levers **13** and **14** may then be pivotally mounted upon corresponding ends of the top horizontal cross members, and the bell crank levers will be vertically swingable and operate in exactly the same manner illustrated in the drawings.

It is to be understood that the form of the invention herewith shown and described is to be taken as a preferred example of the same, and that various changes in shape, size and arrangement of parts may be resorted to without departing from the spirit of the invention or the scope of the subjoined claim.

Having thus described my invention, I claim:

Means for raising and lowering a clothesline comprising a pair of spaced upstanding posts, generally L-shaped bell crank levers pivotally secured to the posts for vertical swinging movement adjacent to corresponding sides of the posts,

the bell crank levers including relatively long first arms adapted to extend transversely of the posts beyond opposite sides thereof, the bell crank levers including relatively short second arms arranged substantially at right angles to the first arms and adapted to extend longitudinally of the upright posts in upstanding and depending positions, attaching eyes secured to the free ends of the relatively short second arms, a substantially horizontal clothesline extending between the posts and having its ends secured to the eyes, and hooks carried by the first arms near their free ends for engagement with the clothesline when the first arms of the bell crank levers are extended transversely inwardly of the posts and the second arms are upwardly directed.
